UNITED STATES PATENT OFFICE.

ROBERT WUFFLI, OF CLEVELAND, OHIO.

SELF-HEATING SAD-IRON.

No. 824,897.

Specification of Letters Patent.

Patented July 3, 1906.

Application filed March 8, 1905. Serial No. 249,091.

To all whom it may concern:

Be it known that I, ROBERT WUFFLI, a citizen of the United States, residing at Cleveland, in the county of Cuyahoga and State of Ohio, have invented certain new and useful Improvements in Self-Heating Sad-Irons; and I do declare that the following is a full, clear, and exact description of the invention, which will enable others skilled in the art to 10 to which it appertains to make and use the same.

My invention relates to improvements in self-heating sad-irons; and the improvement consists in the construction and arrangement of parts substantially as herein shown and 15 described, and more particularly pointed out in the claim.

One of the difficulties encountered in the use of self-heating sad-irons is in maintaining the iron at a uniform temperature over its 20 entire ironing-surface, and especially when the iron is under constant use and engaged with wet and cold surfaces.

A further difficulty is met in supplying the proper amount of air to the burner so that 25 perfect combustion takes place within the iron and also in preventing the flames from escaping at the sides of the iron near its bottom.

My object is to overcome the foregoing 30 difficulties and to provide a sad-iron adaptable to the use of either artificial or natural gas.

In the accompanying drawings, Figure 1 is 35 a side elevation of my improved sad-iron, and Fig. 2 is a front end view thereof. Fig. 3 is a cross-sectional view on line *x* *x*, Fig. 1, and Fig. 4, a central longitudinal section on line *y* *y*, Fig. 3. Fig. 5 is a horizontal sectional view of the iron on line *z* *z*, Fig. 4.

The main body *A* of the iron has the usual 40 flat ironing base portion *2* and end posts *3*, projecting upward therefrom and upon which cover *B* is secured by screws *4*. A handle *C* is bolted to cover *B*, and a strip of 45 asbestos or other heat-insulating material *5* is inserted between said handle and the cover to keep the metal portions out of contact and as cool as possible. A strip of asbestos *6* is also fastened to the bottom of cover *B* to prevent the rising heat from coming in direct 50 contact with the cover.

Body *A* is preferably cast in a single piece 55 with a walled air-passage *7* at each side extending from front to rear conforming to the side edges of base portion *2*, and said channels or passages *7* are open at their ends to

the outer air for the admission of air for gas-burner *D*, but are closed at their outside or outer wall *9* at all points opposite the burner to prevent the egress of the flame which 60 plays over bottom *2* from side to side. Inner walls *10* of passages *7* are provided with a series of openings *11* their full length opposite burner *D* to permit the proper amount of air to commingle with the gas from burner *D*, 65 and thereby promote instant combustion at the very bottom of the iron. The flame generated does not rise much above the top wall of channels *7*, but plays downward and spreads from side to side and fills the space 70 over bottom *2* where it is most needed. I find that by locating the air-admission openings *12* of channels *7* at the extreme ends of the iron and walled from the burner a free supply of air in sufficient quantities can 75 always be obtained to promote proper combustion of all the gases from burner *D* and that no surplus gases escape or are confined within the iron.

Outer walls *9* have an upper beveled edge 80 13, and upon each wall is a side plate *14*, also beveled at its lower edge, which engages edge 13 and continues the side wall of the sad-iron to a short distance below cover *B*. Depending lugs *15* on said cover engage the top edge 85 of plate *14* and hold the same in place. Plate *14* is preferably perforated or slotted in any suitable manner along its full length for the escape of surplus heat.

Burner *D* is a detachable member comprising a tube *20*, which is provided with a series of semicircumferential slots *21*, arranged at uniform distances apart substantially the full length of said tube and at its bottom. A removable plug *22*, semicircular 90 in cross-section and slightly tapering, with a head *23*, is inserted within tube *20* to lessen the gas-confining area within the tube substantially midway of the tube to its outer end, and thereby provide for a more equal 100 distribution of gas the full length of said burner and over the entire surface of the bottom *2* of the sad-iron. I find that without this provision an unequal distribution of gas is obtained and danger of explosion from 105 confined surplus gas is apt to occur, especially when lighting the burner. Tube *20* is screwed into an elbow or casting *24*, which forms a rear inclosing plate fastened by screws *25* upon rear posts *3* and whereby the burner as a whole is supported and fixed 110 upon and within the sad-iron body. A short

pipe 26 is set at an inclination and screwed in casting-plate 24 as a continuation of tube 20 and is threaded at its upper end to permit an adjustable connection with a mixer-cap 27, 5 adapted to support the valved gas-inlet member 28. A series of openings 28' in the side wall of cap 27 admits air to pipe 26 in as great a quantity as may be needed and as determined by the open space between the 10 end of pipe 26 and the opposite surface 29 on cap 27. A jamb-nut 30 locks the cap in the relation as set. By this arrangement either artificial or natural gas may be used in burner D with equal results. When natural gas 15 is used, it is best to use a smaller gas-outlet than for artificial gas, and to this end I provide a tapering screw-threaded tip 31, which is a removable part of member 28 and is adapted to rest and be held by friction or set- 20 screw within tapering seat 32 of cap 27 and whereby one form of tip may be substituted by another. The usual flexible hose con-

nection is made with nipple 33 of member 28 for the supply of gas for burner D.

What I claim is—

In a self-heating sad-iron, a cast-metal body provided with air-passages lengthwise in the sides thereof upon the bottom of the iron, the front ends of said passages inclined inward into the nose of the iron and said passages open at both ends to the outer air and closed to the outer air between their ends and provided with inlet-openings along their inner sides, in combination with a burner centrally over the base of said body and closed at its top and provided with openings 30 along its sides opposite said inlet-openings. 35

In testimony whereof I sign this specification in the presence of two witnesses.

ROBERT WUFFLI.
